United States Patent Office

Des. 210,987
Patented May 7, 1968

210,987

PENCIL CASE

Jack Fairchild Fleming, Summit, N.J., assignor to Sterling Plastics Co., Mountainside, N.J., a corporation of New Jersey

Filed June 21, 1967, Ser. No. 7,545

Term of patent 7 years

(Cl. D74—21)

FIG. 1 is a top plan view of a pencil case embodying my new design, the opposite or bottom plan view being similar in contour;

FIG. 2 is a front elevation thereof;

FIG. 3 is a rear elevation thereof; and

FIG. 4 is an end elevation thereof, the opposite end elevation being similar in appearance.

I claim:

The ornamental design for a pencil case, substantially the same as shown and described.
